UNITED STATES PATENT OFFICE.

JOHN DEWEY PHILLIPS, OF MILFORD, MICHIGAN.

DESIGN FOR A BUTTON.

SPECIFICATION forming part of Design No. 34,058, dated February 12, 1901.

Application filed January 8, 1901. Serial No. 42,561. Term of patent 7 years.

To all whom it may concern:

Be it known that I, JOHN DEWEY PHILLIPS, a citizen of the United States, residing at Milford, in the county of Oakland and State of Michigan, have invented and produced a new and original Design for Buttons, of which the following is a specification, reference being had to the accompanying drawings, forming part thereof, and in which—

- 10 Figure 1 is a perspective view of a button, showing my new design; and Figs. 2 and 3 are respectively end and side elevations of the button, taken in the direction of the arrows 2 and 3 in Fig. 1.
- 15 The button A has in its outer face a depression at A' arranged near the center. From this depression a slit A² extends to the end of the button, the inner end of the slit being shown as terminating at the center of the depression and the latter being curved, as represented. The outer face of the button is

shown as ornamented with the representation of a star at B, the points of same radiating from the depression, the star and the body of the button being in contrasting colors. 25

The sides of the button at C are undercut and formed on straight lines, as shown, while the ends D of the button are inclined to the plane thereof and are parallel to each other.

Having described my invention, what I 30 claim as new, and desire to secure by Letters Patent, is—

The design for a button, as herein shown and described.

In testimony whereof I have signed my 35 name to this specification in the presence of two subscribing witnesses.

JOHN DEWEY PHILLIPS.
